UNITED STATES PATENT OFFICE.

NICK GORGICHUK AND FRED SOLOMON, OF REGINA, SASKATCHEWAN, CANADA.

PANTS STRETCHER AND PRESSER.

1,335,436.

Specification of Letters Patent. Patented Mar. 30, 1920.

Application filed May 1, 1919. Serial No. 294,063.]

To all whom it may concern:

Be it known that we, (1) NICK GORGICHUK and (2) FRED SOLOMON, (1) a citizen of Ukraine and (2) a citizen of the Dominion of Canada, residing at Regina, in the Province of Saskatchewan and Dominion of Canada, have invented certain new and useful Improvements in Pants Stretchers and Pressers, of which the following is a specification.

The primary object of the invention is to provide a ready means for stretching and pressing trousers, retaining the garment until desired for use, the invention possessing great strength and being foldable for packing away when found desirable.

A further object of the invention is to provide a presser and holder for trousers that is easy and inexpensive to manufacture adapted for the ready reception of a garment for holding the same in pressed and stretched condition as long as desired and readily released at will.

With these general objects in view, the invention consists of the novel combination and arrangement of parts hereinafter fully described, illustrated in the accompanying drawing and then claimed.

In the drawing forming a part of this application, in which like reference characters designate corresponding parts throughout the several views,

Figure 1 is an elevational view of the invention with a pair of trousers held therein,

Fig. 2 is an end elevation thereof,

Fig. 3 is a side view of the same,

Figs. 4 and 5 are transverse sectional views taken upon lines IV-IV and V-V respectively of Fig. 1,

Fig. 6 is an enlarged detail sectional view taken upon line VI-VI of Fig. 1,

Fig. 7 is a perspective view of one of the side frame members forming a part of the invention, and

Fig. 8 is a perspective view of a hinged portion of one of the positioning strips employed with the side members.

Referring more in detail to the drawing, a frame is provided for receiving and clamping a pair of trousers therein and comprises a cross head 10 at one end of the invention. Double sides 11 and 12 divergently project from said head being adapted to receive the edge portions 13 of a pair of trousers 14 therebetween with the trousers

suitably folded in the usual manner for stretching purposes.

Each of said sides of the frame comprises two similar side rails 15, the ends of one pair of which are secured to the head 10, each of said rails having laterally projecting arms 16. A pin 17 upon one of each pair of arms 16 slidably projects through a perforation 18 in the adjacent arm while a clamping bolt 19 has its headed end 20 secured in each arm 16 which is provided with a perforation 18, a winged nut 21 being provided upon the other end of each bolt 19 adjacent the arm 16 of each pair provided with one of the pins 17.

The rails 15 are formed in two parts connected by hinges 22 and permitting the sections of the rails farthest from the head 10 to swing relatively outwardly when desired. Strips 23 formed in two sections 24 connected together by hinges 25 are positioned within the opposite sides of the folded garment such as the trouser leg 14 with the edges 13 between the rails 15 at the opposite sides of the invention. The nuts 21 are then tightened securing the rails 15 upon the garment with the strips 23 flatly held between said rails. The strips 23 are shiftable through slots 26 in the head 10.

The end of one of the strips 23 projecting through a perforation 26 of the head 10 is pivoted as at 27 to spaced ears 28 upon the outer side of the head while a corresponding end of the other strip 23 projecting through the relatively longer slot 26' is provided with a pivot 29 slidably mounted in slots 30 of spaced plates 31 upon the outer side of said head 10. This construction permits limited swinging movement of the strips 23 positioned between the rails 15 for accommodating the garment when placing the same upon and taking the garment off of the frame.

The rails 15 constituting one side of the frame are free from the head 10 with the inner ends slideable on the head as shown in Fig. 3. Spacing screws 32 are swiveled as at 33 to a fixed rail 15 of one side of the frame while the screws 32 are threaded through lugs 34 carried by the corresponding movable rail 15 at the opposite side of the frame. With the trousers 14 positioned in the frame and secured as heretofore described, the screws 32 may be turned by means of the heads 35 upon the corresponding ends of the screws for moving the shift-

able side of the frame toward or away from the opposite side of the frame which is fixed to the head 10. In this manner, the garment 14 is stretched laterally while the 5 creases at the edge portions 13 thereof are maintained in the frame in its stretched position for any length of time desired and upon releasing the bolts 19, the rails 15 are separated, permitting the garment to be 10 withdrawn from the frame.

What we claim as new is:—

1. A device of the class described comprising a head, frame sides each consisting of spaced rails divergently extending from 15 said head with the rails of one side secured to the head and of the other side unsecured thereto, clamping bolts connected between the rails of each side of the frame, adjusting screws connected between the sides of 20 the frame, strips at opposite sides of the device pivoted to said head and shiftably positioned between the rails at the opposite side of the frame adapted for the reception of a garment over said strips and between 25 said rails during the operation of the device.

2. A trousers stretcher comprising a head having openings therethrough, spaced rails projecting from said head forming one side of a frame, connecting bolts between said 30 rails, a strip pivoted to the outer side of the head shiftably projecting through one of said openings and positioned between the rails of said side of the frame and a holding member opposite said frame side pivotally 35 connected to the head and extending through the other one of said openings.

3. A trousers stretcher comprising a head having openings therethrough, spaced rails projecting from said head forming one side 40 of a frame, connecting bolts between said rails, a strip pivoted to the outer side of the head shiftably projecting through one of said openings and positioned between the rails of said side of the frame, spaced rails 45 adjustably connected together divergently

arranged with respect to said frame side in abutting relation with said head, a positioning strip adjustably pivoted to the head extending through the other one of said openings and between said last named rails 50 and adjusting screws connected between each pair of rails at the opposite sides of the device.

4. A device of the class described comprising a head having slots therethrough, 55 spaced lugs and spaced plates upon the outer side of said head, a strip through one of said slots pivoted between said lugs, a strip through the other slot slidably pivoted between the said plates, the said strips being 60 formed in hinged sections and a pair of clamping rails for each of said strips adjustably connected together convergently adjacent the opposite ends of the head.

5. A device of the class described comprising a head having slots therethrough, 65 spaced lugs and spaced plates upon the outer side of said head, a strip through one of said slots pivoted between said lugs, a strip through the other slot slidably pivoted between the said plates, the said strips being 70 formed in hinged sections, hinged pairs of rails convergently positioned with respect to said head forming opposite sides of a frame with one side thereof secured and the 75 other side unsecured to said head, clamping bolts between the rails of said sides adapted for securing the rails upon said strips positioned therebetween and adjusting screws swiveled to one side of the frame and having 80 screw threaded connection with the other side thereof adapted for imparting relative movement to the sides of the frame whereby a garment secured upon said strips is adapted for lateral stretching during the 85 turning of said screws in one direction.

In testimony whereof we affix our signatures.

NICK GORGICHUK.
FRED SOLOMON.
